UNITED STATES PATENT OFFICE.

CHARLES MILLS, OF NEWTON, MASSACHUSETTS, ASSIGNOR TO THE PETTEE
MACHINE WORKS, OF SAME PLACE.

DESIGN FOR A GUIDE FOR FLAT-GRINDING MACHINES.

SPECIFICATION forming part of Design No. 28,424, dated March 29, 1898.

Application filed October 14, 1897. Serial No. 655,223. Term of patent 14 years.

To all whom it may concern:

Be it known that I, CHARLES MILLS, a subject of Victoria, Queen of Great Britain, residing in Newton, in the county of Middlesex 5 and State of Massachusetts, have invented a new and useful Design for a Guide for Flat-Grinding Machines, of which the following is a specification, reference being had to the accompanying drawings, forming a part thereof.

In the drawings, Figure 1 is a side view of a guide block or plate embodying my design. Fig. 2 is a plan view thereof. Fig. 3 is a longitudinal section on line 3 3 of Fig. 2, and Fig. 4 a cross-section on line 4 4 of Fig. 2.

The leading or material feature of my design consists in a guide plate or block C, having a convex side face comprising the curved surfaces A and B united at the point a, which forms a small jog or offset. 15

Having described my invention, what I claim as new, and desire to secure by Letters Patent of the United States, is— 20

A design for a guide for flat-grinding machines as herein shown and described.

CHARLES MILLS.
